[57] ABSTRACT

An hydraulically powered impact device intended for rock drilling having a hydraulic fluid section for reciprocatingly powering an impact piston and a non-hydraulic section into which the impact piston as well as a drill stem adapter extend. The non-hydraulic section, which contains a flush medium supply chamber and a rotation transmitting chuck bushing, is connected to a pressure air source for establishing two separate pressure air barriers, the objects of which are to seal off, lubricate and cool the non-hydraulic section.

8 Claims, 1 Drawing Figure

HYDRAULIC IMPACT DEVICE

This invention relates to hydraulic impact devices intended for rock drilling. More specifically, the invention relates to hydraulic impact devices provided with tool rotating as well as flush medium supply means.

Previously known hydraulic impact devices are disadvantageous in that their reliability as regard operation is relatively low. One reason for that is the fact that such impact devices are very sensitive for dust and similar strange particles which very easily cause choking up of the hydraulic system.

Another reason for operation disturbances is that the non-hydraulic section of the impact device, e.g. the section, which is sealed off from hydraulic fluid, is exposed to hard wear and choking up because of poor sealing relative to the ambient.

A further problem concerning hydraulic impact devices is that the parts which are provided with bearing surfaces, for instance the chuck bushing, and which are located in the non-hydraulic section are insufficiently lubricated and cooled. As a consequence thereof, an unacceptable hard wear occurs resulting in too large clearances and a gathering of wear products.

One object of the invention is to effectively prevent dust and similar particles outside the machine as well as flush medium, from the flush medium supply means from getting into contact with the hydraulic system and other sensitive means of the machine.

Another object of the invention is to accomplish a desirable lubrication of the mechanical means, like tool rotating and recoil damping means, which are located within the non-hydraulic section of the device.

Still another object of the present invention is to accomplish cooling of the non-hydraulic section of the device as well as removing of wear products therefrom.

BRIEF DESCRIPTION OF THE DRAWINGS

One embodiment of the invention is hereinafter described in detail with reference to the annexed drawing, which shows a longitudinal section through a separately rotated rock drill having an impact device according to the invention. However, the hydraulic fluid section, intended for actuating the impact piston, is not shown in detail because it is of a conventional type and does not constitute a part of the invention.

DETAILED DESCRIPTION OF ILLUSTRATED EMBODIMENT

The disclosed rock drill comprises a housing 1 which includes an hydraulic fluid section 2 and non-hydraulic section 3, e.g. the section which is sealed off from hydraulic fluid. An impact piston 4 extends from the hydraulic fluid section 2, wherein it is reciprocately powered, into the non-hydraulic section 3. The two main sections of the housing 1 are separated by a packing device which surrounds the impact piston 4 and which comprises a clearance seal ring 6 and a couple of resilient packing rings 7. Between the clearance seal ring 6 and the packing rings 7 there is a drain compartment 9 provided with outlet passages 8 through which hydraulic fluid which might leak across the clearance seal ring 6 is drained.

The non-hydraulic section 3 of the housing 1 accomodates the rear end part of a drill stem adapter 11 which is provided with an axial flush medium passage 10. For this purpose the housing is provided with a tool

aperture 12 at its front end. Moreover, this section of the housing 1 contains a chuck bushing 13 which surrounds the drill stem adapter 11. The chuck bushing is rigidly mounted in a socket wheel 14 which is rotatably powered by a motor 16 through a gear 15. The socket wheel 14 is journaled in the housing 1 by means of two roller bearings 17, 18 and is provided with an outer gear ring which forms a part of the gear 15. For cooperation with the chuck bushing 13, the drill stem adapter 10 is provided with a widened portion 19 the outer contour of which is adapted to that of the aperture in the chuck bushing 13.

Within the socket wheel 14, coaxially with the chuck bushing 13, there is arranged an abutment sleeve 21 for transferring advance forces applied upon the housing to the drill stem adapter. This sleeve 21 is axially displaceable relative to the socket wheel 14 which sleeve is biased toward its forward-most position by means of a spring 22. In this position the abutment sleeve 21 abuts against the rear end of the chuck bushing 13. At its opposite end, the spring 22 rests against a thrust ring 23 which is rotatably journaled within the housing 1 by means of a roller bearing 24 of the axial thrust type.

During drilling, the forward end of the abutment sleeve 21 is arranged to rest against the widened portion 19 of the drill stem adapter 11 for transferring advance forces acting upon the rock drill to the drill stem via the spring 22 and the thrust ring 23. The spring 22 is intended to absorb recoil impact from the drill stem and thereby protect the impact device from undesirable strains. The impact damping effect of the spring 22 enables use of a roller bearing as axial thrust bearing 24.

The housing 1 is provided with two seal rings 26, 27 which are arranged to cooperate with the outer periphery of the socket wheel 14 and which enclose the bearings 19 and 18 and the gear 15. Thereby, this part of the housing is separated from the rest of the non-hydraulic section 3 of the housing 1. The bearings 19 and 18 and the gear 15 are lubricated with grease.

Further, the impact device comprises a flush medium block 28 situated in front of the chuck bushing 13 and intended for supplying flush medium, for instance water, to the flush medium passage 10 of the drill stem adapter 11. For this purpose, the flush medium block 28 contains a flush medium chamber 29 which surrounds the drill stem adapter 11. An annular groove 30 is formed on the outer periphery of the flush medium block 28 which groove communicates with the chamber 29. The annular groove 30 also communicates with a flush medium supply conduit 32 through a passage 33 in the housing 1.

The flush medium chamber 29 is sealed off by means of two packing rings 34, 35 cooperating with the adapter 11 whereas the annular groove 30 is sealed off by means of two packing rings 36 and 37 cooperating with the housing 1.

In the front part of the housing 1, between the flush medium block 28 and the tool aperture 12, a support sleeve 40 is rotatably journaled in the housing 1 by means of a bearing 41. The support sleeve 40 is arranged to form a radial support for the drill stem adapter 11 during drilling.

The non-hydraulic section 3 of the housing 1 is connected to a pressure air source through a conduit 42 and an inlet passage 43. The conduit 42 is connected to a metering device 50 for adding lubricating oil to the

pressure air. The inlet passage 43 is connected to two inlet openings 44 and 45 in the recoil damping part of the housing 1 and to a passage 46 through which pressure air is conducted to the rear end of the support sleeve 40. The inlet opening 44 is located adjacent the axial thrust bearing 24 and the inlet opening 45 adjacent the abutment sleeve 21.

The housing 1 is also provided with two pressure air outlets. One of these is constituted by an annular space formed between the housing 1 and the adapter 11 within the tool aperture 12. The other air outlet is constituted by a passage 48 which interconnects the atmosphere and a drain chamber 49. The latter is located in the rear part of the flush medium block 28 and surrounds the drill stem 11 just in front of the chuck bushing 13.

This air passage arrangement enables establishing of two separate pressure air barriers the objects of which are to obtain a seal relative to the ambient as well as clean blowing, lubricating and cooling of the non-hydraulic section 3 of the housing 1.

The forward-most of the pressure air barriers is constituted by an air flow which extends from the passage 46 through the axial clearance between the support sleeve 40 and the flush medium block 28, and leaves the housing through the support sleeve 40 and the tool aperture 12. Hereby, a forwardly directed, annular air flow is accomplished which air flow acts as a seal around the drill stem adapter 11 and prevents effectively dust and other strange particles from entering the housing 1. By means of this air flow barrier there is also accomplished lubrication and cooling of the support sleeve 40 and the bearing 41.

In order to obtain a more current air flow between the support sleeve 40 and the flush medium block 28, the former may be provided with radially directed grooves at its rear end.

The rear pressure air barrier is constituted partly by an air flow and partly by a pressure air volume. The latter is obtained in that the air flow which passes the inlet openings 44 and 45 is restricted when passing through the machine, whereby the part of the housing 1 which is situated between the flush medium block 28 and the hydraulic seals 6 and 7 is put under pressure. By means of this pressure air volume particles are prevented from travelling backwards through the machine and get into contact with the impact piston 4 and the seal rings 7.

This sealing effect is improved by a flow of pressure air passing through the outer and inner clearances of the abutment sleeve 21 and further through the inner clearance of the chuck bushing 13. This air flow leaves the housing through the drain chamber 49 and the passage 48, and accomplishes lubrication, cooling and clean blowing of all parts located within the non-hydraulic section of the housing.

In order to obtain a more current air flow, the abutment sleeve 21 may be provided with outer and may be also inner axial grooves and the chuck bushing 13 with inner axial grooves. The chuck bushing 13 may also be provided with radial grooves at its rear end.

Two parts of the housing 1 are separated from the air flow, namely the grease lubricated gear zone surrounding the socket wheel 14 and the flush medium zone constituted by the annular groove 30 and the flush medium chamber 29. However, the latter is in itself a seal barrier between the tool aperture 12 and the hydraulic fluid seals 6 and 7, through which zone strange parti-

cles cannot pass. Yet, the flush medium itself may ooze out backwardly, which is a serious problem when water is used as flushing medium. However, flush water that might ooze out cannot reach further backwards in the impact device than to the drain chamber 49 where the pressure air flow brings it out to the atmosphere through the passage 48.

So, the rear pressure air barrier has a very important task in protecting the impact device from leaking flush water. Other, at least as important tasks are to lubricate and cool the different parts of the impact device as well as to transport wear products out of the machine.

The invention is not limited to the shown and described embodiment but can be freely varied within the scope of the claims.

What we claim is:

1. A hydraulic impact device intended for rock drilling, comprising:
a housing and an impact piston, said housing being divided into a hydraulic fluid section in which the impact piston is reciprocately powered, and a non-hydraulic section into which the forward end of the impact piston extends;
a tool aperture provided in the non-hydraulic section for receiving the rear end of a drill stem or drill stem adapter;
a flush medium supply chamber provided in the non-hydraulic section in communication with the tool aperture; and
pressure air supply means provided in the non-hydraulic section of the housing and including means for coupling pressure air in front of and behind the flush medium supply chamber establishing two pressure air barriers in the non-hydraulic section, one in front of and one behind the flush medium supply chamber relative to the impact direction.

2. Impact device according to claim 1 comprising a metering device coupling a pressure air source to said pressure air supply means, said metering device supplying lubricating oil to the pressure air.

3. Impact device according to claim 1 wherein said pressure air supply means comprises passage means in said non-hydraulic section of said housing, said passage means including a first passage extending in front of the flush medium supply chamber and at least one passage extending behind the flush medium supply chamber.

4. Impact device according to claim 1 comprising a rotation transmitting chuck bushing mounted in said non-hydraulic section for cooperation with the rear end of a drill stem or drill stem adapter, the chuck bushing being located between the flush medium supply chamber and the hydraulic fluid section; and said pressure air supply means includes at least one pressure air inlet opening in the housing behind the chuck bushing and an air outlet opening in the housing in front of the chuck bushing, relating to the impact direction, the chuck bushing permitting an air flow therethrough, whereby the rear pressure air barrier is comprised of an air flow extending through said chuck bushing.

5. Impact device according to claim 4 comprising a metering device coupling a pressure air source to said pressure air supply means, said metering device supplying lubricating oil to the pressure air.

6. Impact device according to claim 1, comprising an annular space communicating with the tool aperture and wherein said pressure air supply means includes

means for supplying pressure air to said annular space, the forward pressure air barrier being comprised of an air flow extending out through said annular space.

7. Impact device according to claim 6 comprising a rotation transmitting chuck bushing mounted in said non-hydraulic section for cooperation with the rear end of a drill stem or drill stem adapter, the chuck bushing being located between the flush medium supply chamber and the hydraulic fluid section; and said pressure air supply means includes at least one pressure air inlet opening in the housing behind the chuck bushing and

an air outlet opening in the housing in front of the chuck bushing, relating to the impact direction, the chuck bushing permitting an air flow therethrough, whereby the rear pressure air barrier is comprised of an air flow extending through said chuck bushing.

8. Impact device according to claim 6 comprising a metering device coupling a pressure air source to said pressure air supply means, said metering device supplying lubricating oil to the pressure air.
